UNITED STATES PATENT OFFICE.

WILLIAM H. CORDILL, OF GRAND VIEW, SOUTH DAKOTA.

CAR-COUPING.

SPECIFICATION forming part of Letters Patent No. 695,280, dated March 11, 1902.

Application filed October 19, 1901. Serial No. 79,255. (No model.)

To all whom it may concern:

Be it known that I, WILLIAM H. CORDILL, a citizen of the United States, and a resident of Grand View, in the county of Brule and 5 State of South Dakota, have invented certain new and useful Improvements in Car-Couplers, of which the following is a full, clear, and exact description.

The object of my invention is to provide a 10 device whereby a line of coupled rods or a train of coupled vehicles may be uncoupled at any desired point by turning the line of rods from either end of a train. The device in a modified form may also be used to execute a mechanical movement at any particular point in a line of rods from one end of said line.

I will describe my device as constructed for vehicles and for a line of rods and will point 20 out the novel features in the appended claims.

Reference is to be had to the accompanying drawings, forming a part of this specification, in which similar characters of reference indicate corresponding parts in all the views.

25 Figure 1 is a side elevation of two coupled freight-cars, showing my invention applied thereto. Fig. 2 is a partial longitudinal section on the line 2 2 in Fig. 3. Fig. 3 is a front end view of a coupler proper. Fig. 4 is a partial longitudinal section on the line 4 4 in Fig. 3. Fig. 5 is a partial section on the line 5 5 in Fig. 6. Fig. 6 is a front end view of that portion of the coupler shown in Fig. 5. Fig. 7 is a sectional detail view taken 35 on the line 7 7 in Fig. 6. Fig. 8 is a detail view of a wing-plate employed. Fig. 9 is a view taken on the line 9 9 in Fig. 5. Fig. 10 is a view taken on the line 10 10 in Fig. 5. Fig. 11 is a view taken on the line 11 11 in. 40 Fig. 5. Fig. 12 is a sectional view taken on the line 12¹ 12² in Fig. 13. Fig. 13 is a detail view of a drum, showing a different portion from that illustrated in Fig. 5. Fig. 14 is a cross-section taken on the line 14 14 in Fig. 45 1. Fig. 15 is a sectional view taken on the line 15 15 in Fig. 16. Fig. 16 is a plan view of a sounding device employed. Fig. 17 is a longitudinal section of a modification of my invention. Fig. 18 is a sectional view on the 50 line 18 18 in Fig. 17, and Fig. 19 is a detail view taken on the line 19 19 in Fig. 17.

The coupling-heads are placed inside of a

cylindrical draw-head provided with arms extending outwardly and forwardly, each draw-head being automatically locked to the 55 cylinder of an opposing draw-head. When the rods connecting the couplings are turned, the coupling-heads are unlocked, thus disconnecting the vehicles. By the turning of the rods the coupling-heads of a train are one 60 after another brought under the control of the operator until the coupling is reached which is to be disconnected. Thereupon a single turn of the rod in the opposite direction unlocks the said coupling and all the 65 coupling-heads on the rod will be simultaneously returned to their initial positions.

Mounted beneath each car is a rod 1, one end of which has a rectangular longitudinal bore to receive the similarly-formed end of a rod 70 1^a, arranged to slide in the said rectangular bore of the rod 1. The rod 1^a, Figs. 5 and 13, carries a solid drum 2, said drum having a circumferential groove 3 intersected at right angles on diametrically opposite sides of the 75 drum by a longitudinal groove 4. Both grooves 3 and 4 communicate with each other on opposite sides of the drum by means of an obliquely-ranging groove 5. In this system of grooves rollers 6 are made to travel, as will be hereinafter more fully described, said rollers being journaled in and carried by arms 7, depending from arms 8. The rollers 6 are normally at rest at the junction of the grooves 3 and 4. Behind this junction at opposite 85 sides of the drum 2 lies a spring-pressed bolt 9, seated in a recess, said bolt serving to prevent a backward movement of the rollers 6, as will hereinafter more fully appear. The rollers as they travel in the grooves 3 force aside a 90 spring-pressed gate 10, pivoted on a post 11, the rollers being so mounted as to roll on the gate to reduce friction. This gate 10 normally obstructs the groove 3 at diametrically opposite sides of the drum and closes automatically after the rollers 6 have passed. As the rollers travel onward in the groove 3 they press back a beveled spring-pressed bolt 12, having a portion 13 countersunk in the groove 3 and slidable in a slot 14, (see Fig. 13,) said 100 slot communicating with a recess 15. It is to be understood that there are two bolts 12 and recesses 15 on opposite sides of the drum 2. As each bolt 12 is thrust back against its

spring the countersunk portion 13 makes way for a rack 16, (see Figs. 11 and 13,) actuated by a spring 17, seated in a recess in the drum. The rack thus prevents the bolt 12 from 5 springing back after the rollers have passed. The bolt 12 is pivoted at its outer end to one end of a lever 18, fulcrumed in the recess 15, the other end of the lever being pivoted to a bolt 19, slideable in a slot 20, communicating 10 with the recess 15 and the groove 3. When the bolt 12 and its countersunk portion 13 are pressed back against their spring, the bolt 19 is thrown in the opposite direction through the medium of the lever 18 across the groove 3. 15 After passing the bolt 9 previously described the rollers 6 are confined between said bolt 9 and the bolt 19 in the groove 3. The rollers on opposite sides of the draw-head will now be in the same relative position as they were in 20 starting, with the exception that each has described a half-revolution. On continuing the rotary movement of the arms 8, by means of the rollers 6, abutting against the bolt 19, the drum 2 and likewise the rod 1^a are turned 25 by said rollers. The rod 1^a being rigidly connected at its other end with the similar drum of a second coupling, it follows that another half-turn of the arms 8 produces a like change in position of the parts of the second drum. 30 In other words, a full turn of the first coupling is necessary to cause the second to turn a half-revolution. Thus each half-turn of the rod 1 in the same direction operates another line of rods. Hence to operate a line of seven rods 35 there must be eight turns of the first drum. The operator having made a half-turn of the rod 1 for each coupling-head between his point of operation and the coupling he wishes to disconnect makes a quarter-turn of the rod, thereby causing the rollers 6 in the head to be uncoupled to assume a position slightly beyond the gate 10. By turning the rod 1 backward the operator forces the rollers 6 back against the closed gate 10, which serves to guide the 40 rollers into the groove 5. This movement of the rollers and their arms withdraws the catches which hold together the coupler-heads at this particular coupling, as will hereinafter appear. A spring-catch 21, the bent end of 45 which enters the recess 22, prevents a return movement of the rollers 6 into the groove 5 after they have entered the groove 4. The rack 16 constitutes one of a pair worked in opposite directions by a pinion 23. These 50 racks 16 are alternately engaged by the end of a rock-arm 24, Figs. 11 and 12. The rock-arm is journaled in suitable bearings integrally formed on the circumference of the drum 2. The said rock-arm is provided with 55 a loosely-mounted head 25. The rock-arm 24 and its head are pressed apart by a spring 26 abutting against a pin 27 on the arm and against the inner end of the head. In the head 25 a slot 28 is formed, through which a 60 pin 29 on the arm projects. 65 At each turn of the rod 1 in a different direction the rock-arm 24 is thrown from side

to side, withdrawing the one rack 16 from the path of the countersunk portion 13 of the spring-pressed bolt 12. The rock-arm 24 is 70 pivoted on the lug 24^a somewhat beyond the pinion 23, its head 25 being rocked by the teeth 30 of the stationary circular rack 31. Diagonally-disposed guide-plates 32, Fig. 13, on either side of the arm 24, are secured to 75 the drum for the purpose of forcing the arm 24 to engage the rack 16. As the rollers 6 move onward the bolts 12 cannot spring forward during the temporary absence of the rack 16, because of the pressure of the rollers 80 against the bolts 19; but when the rod 1 is turned in the opposite direction the rollers 6 press against the spring-bolts 9, thus allowing the bolts 12 and 19 to return to their initial positions under the influence of the 85 coil-springs pressing against the bolts 12. The rollers 6 when released in their backward movement from pressure against the bolts 9 are drawn into the groove 4. Hence an operator knowing the combination can 90 turn the rods 1 and 1^a the number of times required to operate a desired coupling and can then disconnect the said coupling by another quarter-turn and a back quarter-turn or more, thereby throwing the parts of all the 95 couplings in the line into their first position. It is immaterial whether the arms 8 and the rollers 6 are turned upon the drum, or vice versa.

The outer end of the drum 2 is secured to 100 or integrally formed with a tube 33, Fig. 5, in line with the rods 1 and 1^a. In this tube longitudinal slots 34 are formed to the number of four, said slots being spaced ninety degrees apart. A pin 35 projects through each 105 slot, said pins having sliding movement in the slots. Fitting snugly within the tube 33 is a disk 36, provided on the surface facing the drum 2 with two pairs of lugs. The inner ends of the pins 35 are held by each pair of 110 lugs. On the tube 33 a clutch-disk 38 is mounted, which disk is provided with two pairs of lugs 39, each pair straddling a pin 35. Thus by means of the pins 35 both disks 36 and 38 are carried together and are rotated 115 together with the tube 33. On the outer surface the disk 38 is formed with teeth adapted to lock with the teeth of a disk 40, mounted on the tube 33 at the ends of the slots 34, said disk 40 being loosely mounted on the tube, so 120 that it has independent rotary movement. The toothed disk 40 is provided with a portion 41, projecting outwardly beyond the teeth of the disk, said portion 41, as clearly shown in Fig. 9, being formed with four tongues 41^a, 125 fitting in the corresponding grooves 42 of a cylindrical casing 43, carrying the arms 8, from which the roller-arms 7 extend. Thus the disk 40 carries with it the arms 8 as it rotates, but is not affected by a longitudinal 130 movement of the said arms owing to the tongue-and-groove connection. The disk 40 on its outer face is formed with a circular series of teeth adapted to interlock with the

corresponding teeth of a loose disk 44, having an elongated hollow hub 45, serving as a slideable exterior cap for the forward end of the tube 33. Said tube 33 is likewise provided 5 with an interior cap 46, against which one end of a coil-spring 47 presses, the other end abutting against the end of the hub 45. The spring serves to hold the disk normally out of engagement with the outer end of the teeth 10 of the disk 40. Through the end of the hub 45 the coil-spring 47, the inner cap 46, and the interior disk 36 a pin 48 passes, consisting of an inner reduced portion 48^a, a body 48, and an enlarged portion 48^b. The inner reduced portion 48^a forms with the body 48 a shoulder 49, against which the disk 36 bears. By means of a pin 50, extending through the portion 48^a, the disk 36 is held to the shoulder 49, the said disk 36, however, having free 15 rotary movement on the reduced portion 48^a of the pin. Hence when the pin is reciprocated it carries both disks 38 and 44 alternately into and out of engagement with the central clutch-disk 40. The outer enlarged end 48^b 20 of the pin is pentagonal in cross-section, the five meeting edges being each provided with a thin tongue 51, Figs. 5 and 6, the ends of the pin portions 48^b abutting against each other when two coupling members are brought together. In the act of coupling the enlarged portion 48^b of the pin encounters the end of a similar pin of the opposing coupling-head and is pushed in against the coil-spring 47. The clutch-disks 44 and 40 being thereby 25 engaged with each other and the disk 38 forced out of engagement with the disk 40, the pin 48 is locked with the arms 8 by means of the tongue 41 of the disk 40 and the grooves in the casing 43. It is the function of the 30 clutch-disks 38, 40, and 44, the tube 33, and the pin 48 to hold the rollers 6 fast in their resting place (the junction of the grooves 3 and 4 in the drum) and during coupling to force the rollers out of this position. The 35 cylindrical casing 43 is surrounded by a second cylindrical casing 53, constituting a coupling-head, the outer end of which is formed with hollow tooth-like projections 54, having inwardly-diverging faces 55 and 56, which 40 meet in downwardly and inwardly inclined edges 57. In Fig. 6 five of these tooth-like projections 54 are shown; but their number may be varied, if so desired.

In coupling two cars together the coupling-head 53 of the one mating member is designed 45 to engage the similar coupling-head 53 of the opposing mating member on the other car, the teeth 54 interlocking, so that the edges 57 of the one head will be received between the 50 corresponding faces 55 56 of the opposing head. For the purpose of thus locking the opposing coupling-heads 53 together I provide the face 55 and the face 56 of each tooth, respectively, with a door-like catch 58 59, 55 formed with corrugations or notches. The catches of the same hollow tooth 54 are hinged so that they may swing inwardly toward each

other through openings 60 61 (see Fig. 7) made in the corresponding faces 55 56. In order that the catches of opposing coupling-heads 70 53 may interlock when the said heads are brought together, they are normally pressed outward beyond the faces of the teeth 54 by springs 62. When opposing coupling-heads are brought together, the outwardly-pressed 75 catches of the one coupling-head will ride over the outwardly-pressed catches of the other coupling-head until the corrugations intermesh, whereupon the two heads will be rigidly connected. For the purpose of breaking this locking engagement of the two coupling-heads 53 the catches are secured each to one end of a chain 63, the other end of the chain being fastened to a ring 64. The chain-ring 64 has a series of inwardly-projecting 80 hook-arms 66, designed to engage the rack 67 of the sleeve 68. The racks and hook-arms serve to lock ring and sleeve together. The inner end of the sleeve 68 is bent to form an outwardly-extending flange 71, and the outer 90 end of the cylindrical casing 43 is bent to form an inwardly-extending flange 72. The flanges 71 72 and the intermediate portions of the cylinders 43 and 68 constitute a race-way for balls 73. By reason of this construction the sleeve 68 is enabled to rotate independently of the cylinder 43, but is compelled to reciprocate with the cylinder 43. Since the chains 63, chain-ring 64, sleeve 68, cylinder 43, and arms 8 are so connected that 95 they reciprocate together, it follows that a longitudinal movement of the arms 8, such as would be caused if the rollers 6 were made to travel in the oblique groove 5 of the drum 2, will draw the cylinder 43, sleeve 68, chain-ring 100 64 and chains 63 inwardly, thereby retracting the catches in the teeth of opposing coupling-heads, and thereby breaking the locking engagement of the said coupling-heads. Between the chain-ring 64 and the toothed head 105 of the cylinder 53 a plate 65 is secured to the inner wall of the casing 53, said plate 65 being provided with openings for the passage of the chains 63 and with a central opening for the passage of the pin 48^b.

The interior wall of the sleeve 68 is provided with integral arms 69, having outer reduced portions 70, projecting through the chain-ring 64 and through openings in the plate 65. The chain-ring 64 is slidable on the 110 reduced portions 70 of the arms 69. These arms serve to communicate the rotary movement of the plate 65 to the sleeve 68.

The inner end of the cylinder or coupling head 53 is grooved to receive two series of 115 balls 74^a and 74^b. These two series of balls are separated by the inwardly-extending flange 75 of a cylindrical casing 76, carried by or integrally formed with the rod 1 and surrounding the drum-head 2. The casing 76 is provided with slots 77, through which the rock-arms 24 extend, as clearly shown in Fig. 11. Keyed fast on the outer end of the casing 76 is a circular rack 78, and keyed fast to the cyl-

inder or coupling head 53, between the ends thereof, is a similar rack 79. The teeth of said racks face each other. Between the circular racks 78 79 a collar 80 is located, said collar being fastened to an outer cylindrical casing 81. Rigidly fastened to the collar 80 are eight lugs 82, Fig. 10, arranged in pairs facing each other across the width of the collar. Each pair of lugs is connected by a rod 83. The lugs are arranged in double pairs at diametrically opposite sides of the collar 80. Each pair of rods 83 is connected by a plate 84, provided at each end with openings. The plate 84 is adapted to slide on the rods 83. At the sides of all the central plates 84 and likewise sliding on the rods 83 are pairs of rings 85, the rings extending around the entire interior circumference of the collar 80. Upon the rods 83 springs 86 are coiled, said springs abutting at one end against lugs 82 and at the other end against the rings 85. The springs 86 serve to press the rings 85 and the central plates 84 to the middle of the collar 80.

Pivoted to the rings 85 and within the same are T-shaped pawls comprising a body 87 and a tooth 87^a. Said pawls are pressed into engagement with the circular racks 78 79 by means of a spring 87^b, as clearly shown in Fig. 10. Each circular rack 78 or 79 as it rotates in the direction of the arrow shown in Fig. 10 will swing the corresponding pawl aside, so that the body 87 will lie at an angle to its ring 85. The end of the body 87 will press the plate 84 flatly against the body 87 of the pawl pivoted to the adjacent ring 85, thus holding the second pawl rigidly with its point 87^a in the teeth of the corresponding rack (79, for example, in Fig. 10) and preventing the rack from turning until the pawl is released. When the arms 8 and the drum 2 are rigidly connected and turning together, the rings 85 are forced by the springs 86 against the central plates 84, and the pawls 87^a are withdrawn from the racks 78 and 79, permitting both racks to turn. This releasing of the rings 85 at the proper time is effected by means of a lever-arm 88, which, as shown in Fig. 5, has a triangular head 88^a, carried outwardly by a post at right angles to the lever-arm 88. Beneath each triangular head rollers 88^b are journaled in the lever-arm 88 and in the head 88^a. The rollers 88^b and the head 88^a constitute a wedge, serving the purpose of forcing apart the rings 85. The lever 88 is extended through an opening 89 in the circular rack 78 and is fulcrumed on a post 90, secured on the casing 76. Rods 91 extend perpendicularly inward from the end of each lever 88 and support the pivot 92 of a wing-plate, which, as shown in Figs. 8 and 11, consists of swinging members 93 and 94. By means of rollers 6^a, journaled in suitable bearings in the ends of arms 7^a, secured to the ends of the arms 8 directly opposite the rollers 6, the members 93 94 of the wing-plates are spread against the casing 76, as particularly shown in Fig. 11. The members of each

wing-plate are thus acted upon by the rollers 6^a when the rollers 6 are in the drum-grooves 4 or in the junction of the grooves 3 and 4. When the wing-plates are thus pressed by the rollers 6^a, the head 88^a of the lever is out of contact with the rings 85; but whenever the rollers 6 are turned out of the grooves 4, allowing the members 93 94 of the wing-plate to move toward each other, as shown in Fig. 8, under the influence of the spring 92^a, so that their edges rest on the inner wall of the casing 76 and so that the pivot 92 is projected toward the drum, then by the force of the coil-spring 90^a, secured to the casing 76 and abutting against each lever-arm 88, each wedge-head 88^a will be forced between the rings 85 until said rings rest upon the rollers 88^b. 85

The casing 81, to which the collar 80 is secured, likewise supports the circular rack 31, engaging the heads 25 of the rock-arms 24, and incloses all the mechanism hereinbefore described. Said casing 81 is formed at one end 90 with a head 81^a and with a hollow cone 81^b, the head 81^a and the apex of the cone 81^b having openings for the passage of the rod 1^a. The drum 2 where attached to rod 1^a is formed with a shoulder, which separates said drum 95 from the head 81^a of the casing 81. The head 76^a of the cylinder 76 fits around said shoulder and is screwed to the drum. It is evident that in place of the shoulder a washer can be employed between the two heads. At 100 the apex of the cone 81^b a pin 95, Fig. 4, is passed through the rod 1^a, said pin serving, in conjunction with the shoulder 76^a of the cylinder 76, to reciprocate the casing 81 whenever the rod 1^a is reciprocated. The outer 105 end of the casing 81 has a removable head 81^c, having a central opening sufficiently large to permit the protrusion of the coupling-head 53. The said head 81^c is formed with flanges for the reception of a roller-bearing 81^d, adapted to 110 travel on the outer surface of the cylinder 53. At diametrically opposite sides the casing 81 is formed with tubes 96, rectangular in cross-section, as shown in Figs. 9 and 11, said tubes extending longitudinally from one flat head 115 of the casing 81 to the other. Within each tube 96 a rod 97 is adapted to slide, to the outer end of which rod a yoke 97^a is screwed, straddling a disk 98. At its inner end the rod is provided with a fork 99, straddling a plate 100, held to slide between two guides 101, formed on the cone 81^b. Each plate 100 is connected with a guide-post 101 by a coil-spring 102 and is formed with a curved slot 100^a to receive a pin 99^a, passing through the two members of 125 each fork 99. The disk 98 is provided with lugs 98^a, Fig. 6, projecting between the teeth 54 of the cylinder 53. In the act of coupling the lugs 98^a are pressed by the teeth 54 of the opposing coupling back against the rear 130 meeting edges of the faces 55 56 of adjacent teeth. This movement is transmitted to the rods 97, and thus to the plates 100. The springs 102 serve the purpose of holding the

lugs 98^a of the disk 98 between the teeth 54 of the cylinder 53 when the coupling is disconnected. On the inclined edges of the plates 100 rollers 103, journaled in the forked ends 5 of the rods 104, are adapted to travel, said ends being adapted to engage the posts 101.

The outer casing 81, containing the mechanism described hereinbefore, is held to slide in a cylinder 105, Figs. 2 and 4, but is prevented from turning by reason of the rectangular tubes 96, which fit in grooves 105^a, Fig. 3, formed on the inner wall of the cylinder 105. The cylinder 105 is connected with an outer barrel or draw-head 106 by the partition 106^a and the head 106^b, both being formed integrally with said barrel. The inner end of the barrel or draw-head is reduced and is provided with a head 106^c and a partition or wall 106^d, thereby forming a chamber 107 for the reception of a plunger 108, carried by a hollow buffer-rod 109, through which the rod 1 passes. The barrel 106 and the cylinder 105 are split longitudinally into halves, the semi-cylinders thus formed being clamped together 25 by means of eyes, through which bolts are passed, as shown in Fig. 1. Each half of the barrel 106 is provided with two ears 110, formed with bearings, in which arms 111 are journaled near the outer end of the barrel or 30 draw-head 106. In width each arm is equal to one-fourth of the circumference of the barrel 106. A strong coil-spring 112 is secured to each arm 111 and to the corresponding half of the barrel 106. The coil-springs hold the 35 arms 111 normally distended. The arms are somewhat curved in cross-section and at their free ends are provided with flanges 111^a. Immediately behind these flanges the arms 111 are formed with grooves 111^d, the flanges 40 and grooves constituting gripping and clutch members, as will be hereinafter more fully described. The grooves 111^d are each intersected at right angles by a longitudinal recess 113, formed with a reduced portion 113^a. At the 45 outer ends of the recess 113 a swinging arm 114 is pivoted, said arm 114 being formed with a groove 114^a, receiving an extension 115, having limited sliding movement in the reduced portion 113^a of the groove 113. The inner end 50 of the telescoping extension 115 is pivoted to a ring 116, provided with inwardly-extending hooks 116^a. The rings 116 are adapted to enter grooves 111^b in the flanges 111^c on the inner ends of the arms 111. The extensions 115 serve to draw the arms 111 inwardly. Each barrel 106 is provided with an annular flange or shoulder 117, designed to be engaged by the groove 111^d and the flange 111^a of an opposing coupling. The draft 60 strain therefore falls upon the arms 111. Each barrel or draw-head 106, as shown in Fig. 1, is supported so that one arm 111 of one coupling will lie opposite the space between the two arms of the opposing coupling.

65 When the arms 111 assume a horizontal position, the extensions 115 will enter the reduced portions 113^a of the grooves 113, and

the rings 116 will strike the flanges 111^c, forcing them into correspondingly-shaped seats in the barrel-head 106^b, so that they lie flush 70 with the surface of said head.

The hooks 116^a of the rings 116 are adapted to engage hooks 119^a, pivoted in the partition 106^a of the barrel 106 and pressed on their inner ends by springs 119^a, secured to 75 the partition 106^a. Extending longitudinally through the barrel or draw-head 106 and through passages in the head 106^b are two rods 120, Figs. 2 and 4, secured to the ring 116 on opposite sides. The inner ends of the rods 120 work between guide-blocks 121, integrally formed with the barrel 106, said blocks having grooves 121^a to receive tongues on the rods 120. The inner ends of the rods 120 are provided with racks 122, meshing 80 with pinions 123, journaled in each pair of blocks. Each pinion 123 meshes with a rack 124, provided with tongues received in grooves in each pair of blocks 121^b. Coiled around the rods 1 and 1^a, between the cone 81^b and 90 the wall 106^d, is a spring 125, which serves to draw the cylinder 81 inward. When each rod 120 is moved in one direction, the corresponding rack 124 is moved in the opposite direction. Pivoted to the ends of the racks 95 124 are the spring-pressed arms 104, carrying the rollers 103, previously mentioned. The arms 104 are outwardly curved or bent to enable the cone 81^b to move inward. Each arm 104 as it is forced outwardly by the rod 120 100 abuts against the guide-blocks 101, and thus pushes the casing 81 outward. When the lugs 98^a, lying between the teeth 54 of one cylinder 53, are pressed back, as above described, by the points of the teeth 54 of an 105 opposing cylinder, the rods 97 are also pushed, so that the spring-arms 104 are disengaged from the blocks 101 by the sliding plate 100.

Coiled around the buffer-rod 109 is a strong spring 126, confined between the ball 127 and 110 the head 106^c of the draw-head 106. As one car is brought against another during coupling the spring is compressed. When the car starts, the spring 126 will react and give sufficient play to the coupling of each car. The 115 ball 127 has a passage-way for the rod 1 and is held in a bracket, Fig. 1, composed of two parts 128^a and 128^b, bolted together, the part 128^a being secured to the bottom of the car. The draw-head 106 is hung from the car in the 120 two halves of a ring or hoop 129, said halves being bolted together, and the upper portion of said ring being provided with an integral hollow post 129^a, in which a rod 129^b slides. The rod is secured to the car and is provided 125 with an enlarged end to prevent its escape from the hollow post 129^a. A spring coiled around the rod allows the draw-head to move sufficiently so that the coupling-arms 111 may grip the flange 117 of the opposing coupling. 130

In order to operate the coupling from the top of the car, I key to the rod 1 a clutch-disk 130 and loosely mount on the rod the clutch-

disk 131. An intermediate clutch-disk 132, toothed on both sides, is secured to a sleeve splined on the rod 1, so that the disk 132 can be drawn from engagement with the disk 130 or the disk 131. To the bottom of the car a bracket is secured, provided with superposed boxes 133 134. The box 133 provides a bearing for the rod 1 and the box 134 a bearing for the rod 135. The box 134 is formed with a flange 134^a to receive a grooved sprocket-wheel 136. By reason of this construction the sprocket-wheel is prevented from moving longitudinally on the rod 135. A chain passes over the sprocket-wheel 136 and around teeth on the clutch-disk 131. The rod 135 near its end is provided with tongues fitting in grooves in the sprocket-wheel 136, so that the sprocket-wheel turns when the shaft is turned. To the shaft or rod 135 is secured a bar 137, the end of which is forked and is received in a groove in the clutch-disk 132. Hence said disk is moved longitudinally along the rod 1 when the rod 135 is moved longitudinally. The rod 135 extends through a yoke 138, connected by pivoted links 139 with a similar yoke 140, through which a vertical lever 141 passes. The yoke 138 is prevented from moving along the rod 135 by pins; but the yoke 140 is free to move longitudinally on the lever 141. The lever 141 and the rod 135 are connected by a flexible joint 141^a, whereby the movement of the one is communicated to the other. The lever 141 is pivoted in a bracket 142, secured to the end of the car, the lever passing loosely through the pivot 142^a, so that it can be both rotated and swung. To the lever one end of a coil-spring is fastened, the other end being secured to the car. The spring serves to hold the lever in proper position relatively to the rod 135 and the rod 1. A spring-clip 144 is fastened to the end of the car, and into this clip the lever 141 is drawn and temporarily held during uncoupling. On the outer end of the lever 141 handle-bars 145 are secured. The lever 141 is likewise provided near its upper end with an indicator or finger 146, Fig. 14, playing over a dial 147, secured to the car by means of a bar 148, passing beneath a strap 149, fastened on the roof of the car. By means of indicating-lines 147^a, which are placed at the end of each quadrant of the dial 147, the finger 146 records the quarter-revolutions made by the lever 141, and hence by the rod 1. In order to give audible as well as visible signals, I provide the dial with four pairs of sounding devices 150, consisting of bells 151, Figs. 15 and 16, mounted in boxes 152 and arranged to be sounded by striking bolts 153, pressed by coil-springs 154, seated in grooves 155. Each bolt has a lug 153^a, which impinges against a bell. The bolts are mounted at an angle to the dial, so that they project slightly above the face of the dial. A spring 153^b holds each bolt in this position. The bells are mounted in pairs in the dial at regular intervals in such a manner that when the finger 146 turns in one di-

rection one set of bells will be struck, while the other set will not be affected. When the finger 146 turns in one direction, it strikes the projecting edges of one set of bolts, forcing each bolt against its spring beneath the face of the dial. When the finger has passed a bolt, the spring 154 will be relaxed and will cause the plate 153 to strike its bell 151. When the finger is turned in the direction opposite the arrow shown in Fig. 15, the other set of bolts 153 is depressed against the springs 153^b without affecting the other bells 151. It is therefore evident that in whatever direction the finger is turned one set of bells will be sounded.

Figs. 17, 18, and 19 represent a modification of my invention applied to a line of rods. In this modified form the outer casing 81 is stripped of all the exterior mechanism shown in Figs. 2 and 4 and is provided with a substantial base 81^c. The tube 33, (shown in Fig. 5,) the clutch-disks on the tube, the pin 48, together with the cylinder 53 and smaller parts connected with these, are dispensed with. The casing 76 is screwed to the drum 2. The outer casing 81 is shortened. Its removable head 81^c and roller-bearings 81^d are in direct contact with the cylinder 43. The said cylinder 43 is solid at one end and formed with a reduced portion 43^a and with an interior bearing 43^b for the shaft 2^a of the drum 2. The ends of the coil-spring 3^b abut against the end of the drum 2 and the solid end 43^a of the cylinder 43. The circular rack 79 is in this modified form of the invention mounted directly on the cylinder 43 and held from moving longitudinally by interior lugs 81^b on the casing 81. The circular rack 79 is held between pairs of blocks 43^c, whereby the cylinder 43 is enabled to move longitudinally independently of the circular rack. Over the reduced solid end 43^a of the cylinder is placed a collar 44^a, to which a head 45^a is secured, said head being carried by the end of a shaft or rod 1, journaled in suitable bearings. The collar is formed with four longitudinal slots 46^a, through each of which a pin 43^b on the cylinder-head 43^a projects. Thus the cylinder is enabled to follow the movements of its arms 8 as the rollers 6 travel in the grooves of the drum 2. The pins 43^b support a grooved ring 47^a, formed in two semicircular parts, which when placed over the pins 43^b are riveted together. The ring is therefore moved as the pins and the cylinder are moved. The connecting-rods of other mechanism may be secured to the ring 47^a to receive the longitudinal movement imparted to the cylinder 43, whereby said movement may be transmitted to any desired coupling in any line of rods or shafts. The circular rack 78 is integrally formed with the cylinder 76 and is provided with guide-blocks 79^a, recessed to receive two racks 79^b and 79^c. In each guide-block 79^a a pinion 80^a is journaled, said pinion meshing with both racks 89^b and 79^c. From this construction it follows that the two racks are reciprocated in op-

posite directions in their respective recesses in the guide-blocks 79^a. As shown particularly in Fig. 18, each rack 79^b is formed with a cam 82^a, adapted to be engaged by the roller 6^a, carried at the end of an arm 8. As the roller rides up the cam the rack is moved outwardly, thereby rotating the pinion and moving the rack 79^c inwardly. As shown in Fig. 17, the rack 79^c carries a wedge-head consisting of the triangular portion 88^a and the rollers 88^b, said head, as previously described, serving the purpose of forcing apart the rings 85. This construction dispenses with the levers 88 and the wing-plates described in connection with Fig. 5. The coil-spring 90^a in this instance again serves the purpose of forcing the wedge-head between the rings 85.

The operation of coupling is as follows: When two cars are brought together and the opposing draw-heads approach each other, the arms 111 of the one draw-head will enter the space between the arms 111 and the other draw-head. The rings 116 of the opposing draw-heads will come in contact with each other and each will be forced back into the corresponding recess 111^b of the flange 111^c on the inner end of the arm 111. The flanges 111^c will thereby be pushed into the seats in the head 106^b, so as to lie flush therewith, and the arms 111 of the one draw-head will be made to grip the flange 117 of the opposing draw-head by means of the flanges 111^a and grooves 111^d. The arms will be held in gripping position by the engagement of the hooks 116^a with the hooks 119^a. As the rings 116, with the flanges 111^c, move toward the head 106^b the rods 120 move inwardly and by means of the pinion 123 force the racks 124 and arms 104 outwardly. The said arms 104 will then abut against the posts 101 and carry the cylinder or coupling-head 53 outwardly until it engages the opposing coupling-head 53. The teeth 54 of the one coupling-head are then pressed against the lugs 98^a of the plate 98 of the opposing coupling, forcing in the rods 97, so that the plates 100 are wedged beneath the rollers 103, thereby disengaging the arms 104 from the posts 101. When the opposing rings 116 meet and each flange 111^c is forced about half-way to the seat in the head 106^b, the casing 81 and coupling-head 53 will be moved out by the rods and racks somewhat beyond the point necessary for the meeting of the coupling-heads 53. Hence when the rings 116 and flanges 111^c complete their journeys to their seats in the respective heads 106^b the coupling-heads force each other inwardly, but without affecting the rods 120, since the rollers 103 will ride up the inclines of the plates 100. At the same time the arms 111 of each draw-head engage the flanges 117^c. When the casing 81 is forced out, the spring 125 is distended. As the coupling-heads 53 meet the faces 55 56 of the teeth 54 of the one will guide the points of the opposing teeth until both coupling-heads 53 are interlocked and the catches 58 59 of the two coupling-heads

are firmly engaged with each other. When the coupling-heads meet, the ends of the pins 48 abut against each other, move inwardly, and free the clutch-disk 38 from the disk 40, thereby breaking the connection of the tube 33, and hence of the drum 2, with the arms 8, and connecting the pin 48 with the arms 8 by locking the clutch-disk 40 with the disk 75 44, the rollers 6 being then free to rotate with the casing 53.

The operation of uncoupling is as follows: The handle-bars 145 are grasped by the operator and the upper end of the lever 141 moved into engagement with the spring-clip 144, the dial 147 being moved with the lever by the sliding of the bar 148 beneath the strip 149. The spring 143 is compressed. By means of the yokes 138 and 140 the lower end of the lever pulls the rod 135, which movement is transmitted to the bar 137, thereby disengaging the clutch-disk 132 from the disk 130 and moving the said disk 132 into engagement with the disk 131. If the lever 141 be turned, a rotary movement will be given to the rod 1 by means of the chain connecting the clutch-disk 131 with the sprocket-wheel 136. Normally the drums of all the couplings are in such a position that the rollers 6 are located in the junctions of the grooves 3 and 4, with the bolts 19 of each drum drawn back into the recess 18. If the operator desires to uncouple, for example, the third coupling from his end of the train, he gives the handle-bars 145 a half-turn to the right, which movement is transmitted to the rod 1 and the rod 1^a by means of the slip-joint between the said rods 1 and 1^a. Depending upon which end of the train the operator may have taken his station, either the drum 2 or the coupling-head 53 will be correspondingly turned. Let it be assumed that in the present instance the drum 2 is thus affected. A half-revolution of the handle-bars 145 will therefore turn the first drum 2 likewise through a half-revolution, the rollers 6 traveling in the grooves 3. As the drum turns the gate 10 is pressed back by the rollers 6, but immediately springs back after having passed the rollers. As the drum continues to rotate the rollers 6 are brought into contact with the bolt 12, which is forced back and held in this position by the rack 16, which is actuated by its spring. Simultaneously the bolt 19 is shot across the groove 3, so that the rollers 6 after having passed the bolt 9 are held between the bolts 9 and 19. Hence by this half-turn of the handle-bars 145 and rod 1 the first drum 2 and the rollers 6 are locked together, so that a further rotation of the handle-bars 145 will turn both drum and rollers together. By giving the handle-bars 145 a second half-turn the drum 2 of the second coupling in the line will be turned by the coupling-head 53. The second drum 2 is thereby made to turn, so that the gate is pressed aside, as before, by the rollers 6, so that these rollers will be finally locked between the bolts 9 and 19 in the manner

already described. Thus the drums of the first two couplings will be rigidly locked together, so that a further rotation of the handle-bars will be communicated to the third drum in the line of couplings. To uncouple the third coupling, the handle-bars 145 are turned only sufficiently to cause the gate 10 to be pressed back by the rollers 6. Then upon a quarter-turn of the handle-bars 145 in the opposite direction the rollers 6 of the said coupling will be caused to travel in the groove 5 (the gate 10 serving as a guide) and to enter the groove 4. By thus deflecting the rollers 6 into the groove 5 the arms 8, sleeve 68, and chain-ring 64 are moved longitudinally, hence disconnecting the catches 58 and 59 of the opposing coupling-heads 53, whereupon these coupling-heads are drawn apart by the distended spring 125 in the respective draw-heads 156. As the parts mentioned are thus moved the hooks 119^a and 116^a are disengaged, (the hook 119^a being thrown inwardly by the retraction of the cylinder 81,) whereupon each spring 112 disengages its arm 111 from the flange 117 of the opposing draw-head, thus disconnecting the members of the desired coupling. In like manner it is possible to disconnect any coupling in the train. When the coupling-heads 53 are drawn apart by the springs 125, each pin 48 under the action of the spring 47 is moved outwardly sufficiently to disengage the clutch-disk 44 from the clutch-disk 40, freeing the pin 48 from the arms 8, engaging the disk 38 with the disk 40, and connecting the arms 8 with the tube 3 and drum 2. By the backward movement of the handle-bars 145 the rollers 6 are forced against the bolt 9, the catch 21 preventing a return of the rollers. By the action of the spring-catches 59 the rollers 6 are drawn along the groove 4 to the junctions of the grooves 3 and 4. The backward movement of the handle-bars 145 furthermore results in causing the rack 31 to actuate the rock-arm 45, so that the rack 16 is withdrawn from the path of the bolt 12, thereby enabling the bolts 12 and 19 to assume their initial positions. Hence all parts of the drum, together with the rollers 6, are restored to their normal places by the single backward movement of the handle-bars 145 in disconnecting the members of any coupling.

The racks 78 79, together with the rings 85, serve the purpose of connecting the casings 76 and coupling-head 53, respectively, with the outer casing 81, while either the cylinder 76 or 53 is independently rotated during the first half-turn of the handle-bars 145. In the present instance when the first half-turn of the handle-bars 145 has finally resulted in locking the rollers 6 between the bolts 9 and 19 a further rotation of the drum 2 will cause the rollers 6^a to engage the pivot 92 of the wing-plate members 93 94, spreading the wing-plates in the manner shown in Fig. 11, and thereby withdrawing the head 88^a of each lever-arm 88 from between the rings 85. As a result of this retraction of the head 88^a

the racks 78 79, coupling-heads 53, and casing 76 will turn, together with the arms 8 and drum 2, in the same direction. The backward turn of the handle-bars 145, engaging the rollers 6^a with the pivots 92, prevents the spring 90^a from forcing the head 88^a between the rings 85 and assuming its normal position.

The operation of the modified form of coupling illustrated in Fig. 17, &c., is essentially the same as in the coupler described in the foregoing. The purpose of the modified construction, however, is merely to transmit a movement from one rod to another in a connected line of rods.

Having thus described my invention, I claim as new and desire to secure by Letters Patent—

1. A coupling comprising a draw-head; swinging coupling-arms mounted on the draw-head; a projection on the draw-head with which the coupling-arms of an opposing draw-head engage when the two draw-heads are brought together; means for holding the coupling-arms in coupling position; and springs connecting the coupling-arms with the draw-head, said springs serving to hold the coupling-arms normally distended.

2. A coupling comprising a draw-head with swinging, spring-controlled arms mounted thereon; a flange on the draw-head with which the coupling-arms of the opposing draw-head engage when the draw-heads are brought together; a ring located within the coupling-arms and connected therewith; hooks on the ring and hooks within the draw-head with which the ring-hooks engage in coupling.

3. A coupling having a draw-head with swinging, spring-controlled arms mounted thereon; a coupling-head within the draw-head; and operating devices between the coupling-arms and the coupling-head, said operating devices serving to move the coupling-head outward and draw the coupling-arms inward to coupling position when the draw-heads are brought together.

4. A coupling, having a draw-head on which coupling-arms are mounted to swing, a coupling-head inclosed by the draw-head, said coupling-head comprising a casing having hollow teeth at its outer end and spring-controlled catches mounted in the teeth, the teeth of one coupling-head being adapted to interlock with the teeth of an opposing coupling-head, and spring-controlled catches to engage the spring-controlled catches of the opposing coupling-head.

5. A coupling, having a draw-head; coupling-arms mounted to swing on the draw-head; a ring located within and connected within the coupling-arms, said ring having hooks; hooks with the draw-head, said hooks being adapted to engage the ring-hooks; a coupling-head mounted to move within the draw-head; and operating devices serving to move the coupling-head outward to engage an oppos-

ing coupling-head when the ring is moved inward by impact with a ring of an opposing coupling.

6. A coupling, comprising a draw-head; 5 coupling-arms mounted to swing on the draw-head; a coupling-head within the draw-head; and operating devices between the coupling-arms and the coupling-head, whereby the coupling-head is caused to move forward to 10 meet the opposing coupling-head when the coupling-arms are swung inward.

7. A coupling, comprising a draw-head; coupling-arms pivoted to the draw-head; a coupling-head mounted within the draw-head; 15 a ring connected with the coupling-arms; a rack-bar connected with the ring and extended within the draw-head; and a second rack-bar actuated by the first-named rack-bar for the purpose of forcing the coupling-head outward 20 when the ring is moved inwardly.

8. In a coupling, the combination with a drum having a circumferential guide, a longitudinal guide intersecting the said circumferential guide, a guide angularly disposed 25 with relation to the other two guides and connecting the same, and spring-actuated barriers arranged in relation to the guides; of a cylinder movable longitudinally and revolvably with respect to the drum, arms projecting 30 from the cylinder and embracing the drum, and rollers on the arms, said rollers having movement in the guides of the drum and being adapted to be locked by the barriers to the drum.

35 9. In a coupling, the combination with a drum having a circumferential guide, a longitudinal guide communicating with the circumferential guide, a guide angularly disposed with relation to the other two guides 40 and connecting the same, and barriers arranged in relation to the circumferential guides, said barriers comprising a spring-controlled bolt adapted to move in a longitudinal groove in the drum and connected with one 45 end of a pivoted lever, a bolt with which the other end of the lever is connected to be actuated in unison with the first-named bolt, and a spring-controlled bolt arranged to move longitudinally in the drum between the two 50 first-named bolts; of a cylinder movable longitudinally and revolvably with respect to the drum, arms projecting from the cylinder and embracing the drum, and rollers carried by the arms, said rollers having movement in 55 the guides of the drum and being adapted to be locked between the second and third mentioned bolts after having pressed aside the first-mentioned bolt.

10. The combination of a drum having a 60 guideway; a member adapted to be coupled to the drum, said member having its parts received in the guideway; movable barriers for engaging the parts received in the guideway; and means for actuating the barriers to lock 65 or release the parts received in the guideway.

11. In a coupling, coupling-sections which comprise a coupling-head mounted to move

longitudinally, and longitudinally-ranging operating devices movable beyond the coupling-head for impact against similar operating devices on an opposing coupling-section; and means acting on the coupling-head and actuated by the said longitudinally-ranging operating devices, to force the coupling-head outward into engagement with the opposing 75 coupling-head.

12. In a coupling, coupling-sections which comprise a coupling-head mounted to move longitudinally, and longitudinally-ranging operating devices movable beyond the coupling-head for impact against similar operating devices on an opposing coupling-section; 80 means acting on the coupling-head and actuated by the said longitudinally-ranging operating devices, to force the coupling-head 85 outward into engagement with the opposing coupling-head; and a retractile spring for returning the coupling-head to inner position.

13. In a coupling, coupling-sections which comprise a coupling-head mounted to move 90 longitudinally, and longitudinally-ranging operating devices movable beyond the coupling-head for impact against similar operating devices on an opposing coupling-section; means acting on the coupling-head and actuated by the said longitudinally-ranging operating devices, to force the coupling-head 95 outward into engagement with the opposing coupling-head; and means for disengaging the coupling-head. 100

14. A coupling, comprising a draw-head; arms mounted to swing on the draw-head; a coupling-head mounted to have longitudinal movement in the draw-head; operating devices for simultaneously causing the coupling-head to move forward and the coupling-arms to swing inward when two draw-heads are brought together; a drum having a guideway and movable barriers for the guideway; a member arranged to be held between the 110 barriers of the drum-guideway; means for actuating the barriers to lock or release the said member; and means for locking the drum member and the coupling-head together.

15. A coupling, comprising a draw-head; 115 swinging spring-controlled coupling-arms mounted on the draw-head; a ring connected with the coupling-arms; a longitudinally-movable coupling-head within the draw-head; operating devices actuated by the ring 120 for simultaneously forcing the coupling-head forward to engage the coupling-head, and the coupling-arms inward; a drum having guides and movable barriers for the guides; a cylinder, an operative connection between 125 the cylinder and the coupling-head; and arms projecting from the cylinder and embracing the drum, said arms having parts adapted to be locked in barriers in the drum and arranged, when moved longitudinally on the drum, to release the coupling-head from the opposing coupling-head.

16. In a coupling, the combination of a coupling-head having hollow teeth adapted to in-

terlock with the teeth of an opposing coupling-head; catches mounted in the hollow teeth and arranged to engage the catches in the teeth of an opposing coupling-head; a pin 5 on which the coupling-head is arranged to slide, a cylinder, a clutch for connecting or disconnecting the cylinder and pin; a connection between the catches of the coupling-head teeth and the said cylinder; and means 10 for longitudinally moving the cylinder to retract the said catches, whereby the coupling-head is released from the opposing coupling-head.

17. In a coupling, the combination of a longitudinally-movable coupling-head having teeth; catches in the teeth; a cylinder having arms; operating devices for retracting the catches, said operating devices being actuated by a longitudinal movement of the 15 cylinder; and a rotatable drum having arms, and barriers between which the cylinder-arms are locked in the guides, the drum when turned in one direction causing the arms to move the cylinder longitudinally in 20 order to retract the catches of the coupling-head teeth.

18. In a coupling, the combination of a drum having guides and barriers for the guides; a casing for the drum revolvable therewith; a 25 coupling-head having hollow teeth adapted to interlock with the teeth of an opposing coupling-head; spring-pressed catches in the teeth, said catches being adapted to engage similar catches in the teeth of an opposing 30 coupling; means for connecting or disconnecting the drum-casing and the coupling-head; and a cylinder between the drum and the drum-head, said cylinder being connected with the catches of the coupling-head and 35 with the arms received in the guides of the drum, said arms when moved longitudinally 40 on the drum serving to disconnect the catches of the one coupling-head from the catches of the opposing coupling-head.

45 19. A coupling, comprising a draw-head, swinging, spring-controlled members mounted on the draw-head; a coupling-head mounted to rotate and to reciprocate in the draw-head, said coupling-head having hollow teeth 50 adapted to interlock with the teeth of an opposing coupling-head; a ring connected with the members on the draw-head, operating devices actuated by the ring on impact with the ring of an opposing coupling to draw the members 55 on the draw-head inwardly and to force the coupling-head outwardly into engagement with the opposing coupling-head; a pin on which the coupling-head is carried; a clutch operated in one direction by the pin and in the 60 other direction by a spring; a drum having guides and movable barriers for the guides; arms received in the guides of the drum and

arranged to retract the catches of the coupling-head teeth when moved longitudinally inward on the drum, the barriers of the drum 65 serving to lock the arms in the guides; a casing inclosing the drum; a circular rack mounted on the said casing; a circular rack mounted on the coupling-head; and operating devices for connecting or disconnecting the two circular racks, said devices being actuated by the arms to connect or disconnect the coupling-head and drum-casing.

20. In a coupling, the combination of a coupling-head having teeth; spring-pressed catches 75 mounted in the teeth; a pin on which the coupling-head is carried; a drum having guides, and barriers for the guides; a cylinder between the drum and the coupling-head, said cylinder having arms, portions of which are 80 received in the guides and locked between the barriers, the cylinders serving as means for retracting the catches; a casing for the drum; a circular rack on the said casing; a circular rack on the coupling-head; a locking connection 85 between the two racks, and means for releasing the said locking connection, said means being actuated by the arms in the drum-guides.

21. In a coupling, the combination with a 90 drum having a circumferential guide, a longitudinal guide, an annularly-disposed guide connecting the other two guides, and movable barriers for each of the guides; of a spring-pressed rack slidably mounted in the 95 drum and arranged to hold the barriers of the circumferential guide in one position; a rock-arm connected at one end with the said rack, and a circular rack surrounding the drum, against which circular rack the other end of 100 the rock-arm abuts, the rock-arm serving to operate the drum-rack so that the barriers of the circumferential guide of the drum may return to their normal positions.

22. A coupling, comprising a draw-head, 105 swinging, spring-controlled arms mounted on the draw-head; a coupling-head mounted within the draw-head; a casing surrounding the coupling-head, through which casing the coupling-head projects; operating devices 110 whereby the arms on the draw-head are drawn inwardly and the coupling-head and its casing forced outwardly during coupling; and a retractile spring serving the purpose of drawing the coupling-head and its casing back into 115 inoperative position.

In witness whereof I have signed my name to this specification in the presence of two subscribing witnesses.

WILLIAM H. CORDILL.
